Patented Nov. 23, 1915.

Pasquino Ferrari.

UNITED STATES PATENT OFFICE.

PASQUINO FERRARI, OF FALL RIVER, MASSACHUSETTS.

LOOM-SHUTTLE.

1,161,646.

Specification of Letters Patent. Patented Nov. 23, 1915.

Application filed September 10, 1914. Serial No. 861,060.

To all whom it may concern:

Be it known that I, PASQUINO FERRARI, subject of the King of Italy, residing at Fall River, in the county of Bristol and State 5 of Massachusetts, have invented certain new and useful Improvements in Loom-Shuttles, of which the following is a specification.

My invention relates to new and useful improvements in loom shuttles and has particular reference to an improved hand 10 threading device therefor.

One of the principal and more general objects of my invention is to provide means whereby the shuttle may be readily threaded 15 by hand with a minimum expenditure of time.

A further object of my invention in this connection is to provide a threading device which is located in the threading recess of 20 the shuttle and is provided with a threading beak or lip so arranged with relation to the delivery terminal of the eyelet that the thread may be quickly applied to the eyelet and passed through the side of the 25 shuttle by merely being looped and then drawn around the threading beak.

A further object of my invention is to eliminate the necessity of sucking the thread 30 through the threading recess and delivery kerf adjacent the beak of the shuttle, which has heretofore existed in loom shuttles.

An object of equal importance with the foregoing is to so design the threading device that it will be no longer necessary to 35 form, as is now the custom, a diagonally extending delivery kerf emerging at its terminal into the face of the shuttle, the shuttle being provided instead with an opening which emerges at one side in the face of the 40 shuttle and at its other side into the threading recess.

A still further object of my invention is to provide a threading device which may be cheaply formed from a single sheet metal 45 blank and may be easily and readily inserted in or removed from the threading recess of the shuttle.

Another object is to provide the delivery 50 terminal of the thread eye which is formed in the same blank constituting the threading device, with a guard so arranged as to offer little or no resistance to the entrance of the thread into the eyelet during the threading operation but so located that it 55 will make it impossible for the thread to

balloon outwardly with the resultant displacement from the eye.

The above and other incidental objects of a similar nature which will be hereinafter more specifically treated are accomplished 60 by such means as are illustrated in the accompanying drawings, described in the following specification and then more particularly pointed out in the claim which is appended hereto and forms part of this application. 65

With reference to the drawings, wherein there has been illustrated the preferred embodiment of this invention as it is reduced to practice, and throughout the several views of which similar reference characters designate corresponding parts, Figure 1 is a perspective view illustrating the threading device in position within the thread recess; Fig. 2 is a top plan view of 70 the shuttle; Fig. 3 is a side view of the shuttle partly in section. Fig. 4 is a detailed perspective view of the threading device removed from the shuttle; Fig. 5 is a section on the line 5—5 of Fig. 4; and Fig. 6 75 is a detailed plan view of the blank from 80 which the threading device is constructed.

In the accompanying drawings I have illustrated my threading device which is designated as an entirety in Fig. 1 by the letter 85 A as applied to a shuttle B which is for the most part constructed on standard lines including as it does a longitudinally extending opening 10 within which a cop or bobbin 11 is removably held by a spring holding 90 device 12 of well-known construction. At the forward end of the shuttle and in communication with the cop chamber 10 is formed a threading recess designated generally in Fig. 1 by the numeral 13. Within 95 this recess 13 is removably positioned the threading device A.

Before further describing the exact form of the threading recess 13 and the manner in which the member A is positioned therein I deem it advisable to submit a detailed description of the sheet metal blank from 100 which the threading device is formed. For this purpose therefore reference will now be had particularly to Fig. 6. It will there be seen that the end edges of the blank, indicated at 14 and 15, are straight and extend in parallel relation to each other. The rear edge of the blank, indicated at 16, is 105 straight for a portion of its length but ad- 110

ja¹cent the edge 15 it is cut inwardly as at 17 along a substantially V-shaped line. The one edge 18 of this V-shaped kerf in connection with a slightly curved edge 19 which 2 is in reality a continuation of the straight edge 15, defines a triangular tongue 20. This tongue 20 is adapted, when rolled properly in a manner to be hereinafter more fully described, to form a guard member 10 so located that it will prevent the displacement of the thread from the eye of the device. In this connection it may be well to explain that the eye of the threading device which is indicated at 21 in Fig. 1, is defined 15 by the straight edge portion 15 when the shaping of the blank has been completed. The forward edge of the blank is as indicated at 22 cut along a curved line which is substantially semi-circular. The inner 20 terminal of the curved edge 22 merges into a straight edge 24 which latter defines one side of a guide slot 25 through which the thread from the bobbin passes. This edge 24 is substantially straight throughout the 25 major portion of its length but is curved at its outer end to merge into the rounded end 26 of the threading beak 27. It will now be noted that the threading beak 27 is defined by the straight edge 24 and 30 curved edge 22 and is therefore substantially spatulate. The inner end 28 of the slot 25 is rounded so that the thread which bears thereagainst during the use of the shuttle will not be liable to be severed as 35 might be the case were the inner terminal of the slot straight. The outer end of the straight edge 29 which defines the rear side of the slot 25 is curved as at 30, and merges into the forward transverse edge 31 of an attaching ear 32, producing a rounded nose indicated at 33. This attaching ear 32 is adapted to be employed in connection with a pin 34 in securing one end of the threading device in proper position within the recess 13 as will be hereinafter more fully explained. At the outer end of the blank there is formed a substantially U-shaped kerf 35 which as will be seen frees a tongue 36. This tongue 36 is apertured as indicated at 40 45 and constitutes the attaching ear by which the outer terminal of the device is secured within the shuttle. A pin, indicated at 38, is passed through the shuttle and through the member 36 as will also be 50 55 hereinafter explained.

It is now to be noted that the outer end of the curved edge 22 merges, as indicated at 39, into the straight edge 15 at a point which is located in the rear of the rounded end 26 of the beak. The purpose in this 60 particular formation of the edge 22 will be described in that portion of the specification devoted to a description of the use of the threading device.

65 From the blank above described the

threading device as shown in detail in Fig. 4 is formed. Upon reference to this figure it will be seen that during the manufacture of the article the blank has been rolled over a rod-like former which is applied transversely to the blank along the dotted line 40 so as to produce the tubular portion 41. In this connection it will be observed that the former is applied to the under face of the blank and that the rear edge portion 16 70 is then rolled downwardly and thence around the former so as to dispose the straight edge 16, after the rolling of the blank, in advance of the dotted line 40. Thus the guard member 20 which is also 75 rolled into substantially annular form, as shown in Figs. 4 and 5, is disposed so that its apex portion projects within the opening defined by the kerf 35. In this connection it will be observed that during the 80 formation of the blank the tongue 36 is bent upwardly and then directed at an upward and rearward angle so as to leave the opening defined by the kerf 35 unobstructed. The apex portion of the guard 20 extends 85 as best shown in Figs. 4 and 5, to a point slightly above the upper face of the base portion of the beak 27. It is now to be explained that the guard member 20 is rolled in such manner that the curved edge 19 90 extends inwardly and diagonally from the edge 15. After the tubular member 41 has been formed, the attaching ear 36 has been bent to extend rearwardly, and the guard 20 has been properly shaped and disposed 95 with its apex extending into the kerf 35, the beak 27 is shaped. As previously stated the member 27 is of a spatulate shape being transversely and longitudinally 100 curved.

105 Before describing the manner in which the threading device A is positioned in the recess 13 it may be well to particularly describe the formation of this recess. As will be seen upon reference to Figs. 1, 2 and 3, the recess is in plan torpedo shaped. The one wall of the recess indicated at 41 extends in a vertical plane and longitudinally with respect to the shuttle. At its forward 110 terminal, indicated at 42, this wall curves inwardly toward the center of the shuttle until it meets the inner end of the wall 43 at the point 44. The wall 43 is substantially flat throughout the major portion of its 115 area and slopes diagonally toward the face of the shuttle in a downward and rearward direction, as will be best seen upon an inspection of Figs. 1 and 3. The outer portion of the wall 43 defines the bottom of a 120 thread delivery opening 45 which is formed in the side of the shuttle. At the rear end of the wall 43 is a countersunk transverse channel 46 which is adapted to receive the tubular portion and the eye 21 of the guard 125 as will be seen by reference to Figs. 1 and 3. 130

At this point it should be observed that the shoulder 47 which is defined by the forward end of the opening 10 and the channel 46 is curved at the upper edge of its rear 5 face as indicated at 48 so that the thread as it unwinds from the cop 11 will pass over a rounded surface and will not therefore be frayed. It will also be noted that the inner end 28 of the thread slot 25 is disposed below 10 the upper face of the shoulder 47.

When the threading device is positioned within the threading slot 13, the cylindrical or tubular portion 41 is disposed within the transverse channel 46 as will be best seen 15 upon reference to Fig. 3. As has been previously explained the threading device is secured within the recess by the pins 34 and 38 which are inserted through the apertures of the attaching ears 36 and 32. In this connection 20 it is to be noted that the ear 33 is received within a kerf which is formed in the wall 41 of the recess in the manner indicated in dotted lines in Fig. 2. It will now be noted that the threading beak 27 is 25 curved so that its major portion extends in parallel spaced relation to the downwardly and rearwardly inclined wall 43 of the threading recess. The terminal portion or apex 26 of the beak, however, is bent so 30 that instead of projecting into the wall 41, it lies in approximately parallel relation thereto. At this point it may be well to explain that the lower edge of the wall 41 is slightly curved so as to merge into the 35 curved or rounded upper portion of the wall 43 as indicated at 49 in Fig. 3. When the threading device has been positioned within the recess the guide slot 25 extends diagonally with respect to the longitudinal axis 40 of the shuttle. The thread delivery eye 21 which is defined by the edge portion 15 of the device, opens through the face of the shuttle and is disposed, as has been previously explained, within the thread delivery 45 opening or passage 45.

The manner in which the device above described may be employed in accomplishing the threading of the shuttle will now be readily appreciated, for it will be seen that 50 if the thread is looped and engaged with the apex portion of the beak, a pull exerted on

the free terminal of the thread will cause the same to ride around the curved edge 22. When the thread reaches the outer terminal of this curved edge 22, it of course enters 55 the open eye defined by the straight edge 15. The operator may then grasp with his finger or with some suitable instrument the loop portion which has been thus disposed within the eye and withdraw from the cop 60 chamber the free end of the thread. It should now be noted that the thread may readily enter the eyelet since the convex face of the guard 20 is presented to it as it (the thread) rides down the curved edge 32. 65 However, when the thread passes completely into the eyelet after having moved over the apex of the guard member 20 it will be prevented from withdrawal from the eye since the apex of the guard presents its concave face 70 to the thread and is disposed slightly above the uppermost point of the eye. When the shuttle is in use the thread is fed directly from the cop over the rounded shoulder 47 through the guide slot 25, and out through 75 the eye 21. A longitudinally extending groove 50 is of course provided in the face of the shuttle for the usual purpose of receiving the thread.

Having thus described the invention, what 80 is claimed as new is:—

A threading device for loom shuttles comprising a tubular member having an eye and a tongue at one end and having a portion partly cut from a side of the eye and bent 85 outwardly to form an attaching ear and having the tongue projecting into the cut away portion of the eye, said tubular member having a longitudinal opening formed in a side of its opposite end portion in the rear of the 90 eye, a longitudinally flared and partially twisted beak in the rear of the eye and spaced from the tubular member, and a second attaching ear at the end of the tubular member opposite that provided with the 95 eye.

In testimony whereof I affix my signature in presence of two witnesses.
